[57] CLAIM

The ornamental design for a swizzle stick, substantially as shown.

DESCRIPTION

FIG. 1 is a front elevation of the swizzle stick, showing my new design, the rear elevation being a mirror image of the front elevation;

FIG. 2 is a top plan view thereof;

FIG. 3 is a bottom plan view thereof;

FIG. 4 is a right side elevation thereof, the left side elevation being a mirror image of the right side elevation.

FIG. 1.

FIG. 4

FIG. 2.

FIG. 3.
